CLAIM

The ornamental design for a combined bottle and cap, as shown and described.

DESCRIPTION

FIG. 1 is a perspective view of a combined bottle and cap showing our new design;

FIG. 2 is a front elevational view thereof;

FIG. 3 is a side elevational view thereof, the opposite side elevational view is a mirror image;

FIG. 4 is a rear elevational view thereof;

FIG. 5 is a top plan view thereof;

FIG. 6 is a bottom plan view thereof;

FIG. 7 is a side elevational view of an alternate embodiment of the combined bottle and cap, the top and bottom plan views are the same as those shown in FIGS. 5 and 6;

FIG. 8 is a perspective view of another alternate embodiment of our new design;

FIG. 9 is a front elevational view of FIG. 8;

FIG. 10 is a side elevational view of FIG. 8, the opposite side elevational view is a mirror image;

FIG. 11 is a rear elevational view of FIG. 8;

FIG. 12 is a top plan view of FIG. 8; and,

FIG. 13 is a bottom plan view of FIG. 8.
